UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING CHEEK-PLATE.

1,290,309.

Specification of Letters Patent.

Patented Jan. 7, 1919.

Application filed November 16, 1916. Serial No. 131,616.

To all whom it may concern:

Be it known that I, JOHN F. O'CONNOR, a citizen of the United States, residing at Chicago, in the county of Cook and State 5 of Illinois, have invented a certain new and useful Improvement in Draft - Rigging Cheek-Plates, of which the following is a full, clear, concise, and exact description, reference being had to the accompanying 10 drawings, forming a part of this specification.

This invention relates to draft rigging cheek plates.

One object of the invention is to provide 15 a cheek plate or stop casting for draft riggings having great strength and of substantially uniform thickness throughout, the casting being provided with a series of horizontal convolutions extending from end to 20 end of the casting to give the plate the effect of great thickness without actually thickening the metal, all of the stops of the casting being formed by vertical walls spaced from said horizontal convolutions and connected 25 thereto by horizontal webs.

Another object of the invention is to provide a stop casting having a series of horizontally extending convolutions but which is free from vertical convolutions.

In the drawing forming a part of this 30 specification, Figure 1 is a side elevation of a stop casting showing one embodiment of my invention. Fig. 2 is a horizontal sectional view taken substantially on the line 2—2 of 35 Fig. 1. And Figs. 3, 4, 5, 6 and 7 are vertical sectional views taken on the lines 3—3, 4—4, 5—5, 6—6 and 7—7, respectively, of Fig. 1.

In said drawing, the stop casting or cheek 40 plate is designated generally by the reference A and is shown as of the tandem type having front main stop 10, rear main stop 11, center main stop 12 and intermediate stops 13 and 14. The casting consists of a 45 web of substantially uniform thickness which is convoluted throughout its entire height with alternately outwardly and inwardly facing convolutions 15, 16, 17, 18 and 19. Said horizontal convolutions may

be considered as formed by alternately 50 bending the web inwardly and outwardly, thus giving the casting great strength against longitudinal strains and transverse bending strains. At the same time, the casting is given the effect of great thickness so 55 that the bearing or wearing surfaces for the ends of the followers are spaced a considerable distance from the planes of the draft sills to which the stop casting is adapted to be secured. By this method, the stop castings are adapted to be applied to metal draft sills which have been substituted for wooden 60 draft sills on old gears and the old gears proper reemployed. Where the casting is riveted to the sills, the horizontal convolutions 16 and 18 are slightly enlarged as indicated at 20—20 to accommodate the end of the riveting tool.

The main and limiting stops are, in effect, built on to the horizontal convolutions and 70 this is accomplished by providing vertical webs 21, 22, 23, 24 and 25 for the respective stops 10, 11, 12, 13 and 14. Each of said vertical webs 21, 22, 23, 24 and 25 is connected to the body portion of the casting by 75 a series of horizontal connecting webs 26—26, there being six of said horizontal webs 26 for each vertical web or wall. As clearly appears from Figs. 2 to 6 inclusive, the vertical web 23 is spaced farther from 80 the body of the casting than the end vertical webs 21 and 22 and the latter in turn are spaced farther from the body of the casting than the vertical webs 24 and 25. This is done in order to make the center posts deeper 85 than the end posts and the latter deeper than the limiting stops for the well known purpose of permitting swinging movement of the yoke of the draft rigging about the center post as a fulcrum.

I claim:

As an article of manufacture, a stop casting for railway draft riggings comprising, a main body portion having the web thereof flat on its outer side and adapted to be secured to a metal draft sill, said web being provided with a series of horizontally extending convolutions continuous throughout 95

the length of the casting, said casting having also a plurality of main stops integrally formed and located on the inner side of said casting, each of said stops consisting of a vertical web spaced inwardly from said convolutions and connected thereto by a series of horizontal webs, each of said vertical stop

webs extending from the top to the bottom of the stop and the front and rear sides of each stop being open.

In witness that I claim the foregoing I have hereunto subscribed my name this 11th day of Nov., 1916.

JOHN F. O'CONNOR.
